UNITED STATES PATENT OFFICE.

DAVID HOWE, OF UPSON, WISCONSIN.

MEASURE.

No. 894,953.

Specification of Letters Patent.

Patented Aug. 4, 1908.

Application filed April 1, 1908. Serial No. 424,508.

To all whom it may concern:

Be it known that I, DAVID HOWE, a citizen of the United States, residing at Upson, in the county of Iron and State of Wisconsin, 5 have invented certain new and useful Improvements in Measures, of which the following is a specification, reference being had to the accompanying drawings.

My invention relates to improvements in 10 measures for grain and the like, and it consists of a body having a hinged bottom and an improved catch device for holding the bottom closed and releasing it when it is desired to discharge the contents of the meas- 15 ure.

With the above and other objects in view, the invention consists of the novel features of construction and the combination and arrangement of parts hereinafter fully de- 20 scribed and claimed, and illustrated in the accompanying drawings, in which

Figure 1 is a perspective view of my im- 25 proved measure; Fig. 2 is a vertical sectional view; Fig. 3 is a horizontal section taken on the plane indicated by the line 3—3 in Fig. 2 and Fig. 4 is a detail view of the upper portion of the measure showing its suspending hook.

My improved measure has a cylindrical 30 body 1 which may be tapered slightly towards its lower end if desired and which may be provided at one or more points with horizontal graduation marks 2. But one of these marks is illustrated and that one is 35 centrally arranged. The lower end of the measure body is open and adapted to be closed by a swinging bottom 3 which is hinged as at 4 to a flange 5 formed on the rear side of the lower end of the body 1. 40 Suitably secured to the free front portion of the bottom 3 is a keeper 6 adapted to engage a pivoted catch 7 arranged upon the front of the body 1. Said keeper 6 is right angular in shape and has one arm disposed horizon- 45 tally and secured to the bottom 3 and its free arm extending vertically is bent outwardly at right angles to provide a shoulder 8, and then upwardly and inwardly to provide an inclined portion 9. The catch 7 is in the 50 form of a lever pivoted intermediate its ends at 10 between oppositely disposed angular brackets 11 secured to the body 1. The catch lever is substantially as long as the measure body is high and its upper end forms 55 a handle which permits its lower end to be readily released from the keeper 6. This

lower end of the catch lever is beveled as at 12 and has formed in its inner edge above the beveled portion a V shaped notch which provides a shoulder 13. The latter is adapt- 60 ed to engage the shoulder 8 on the keeper 6 to retain the bottom 3 in its elevated or closed position and when the said bottom is swung upwardly to such position the beveled or inclined portions 9, 12 on the keeper and catch respectively are adapted to ride over each other. The lower end of the catch lever is actuated in an inward direction and is reinforced or guided by a leaf spring 14 the upper end 15 which is arranged beneath 70 the angular brackets 11 and secured to the body 1 and the lower free end which is bent at right angles to provide an outwardly projecting arm 16 formed with a slot or opening 17 to receive the lower portion and catch 75 lever 7.

For the purpose of enabling the measure to be conveniently hung upon a barrel, box, bin, or the like, I provide upon the top of its rear side a suspending hook which is preferably 80 constructed as illustrated in the drawings. This hook is made from a metal rod or heavy wire by bending a piece of the same upon itself at its center as shown at 18 and to provide parallel portions 19 and then bending 85 said portions upon themselves as shown at 20 to provide hook arms 21. The portions 18, 19 of the hook are secured to the body 1 upon its outer side, by means of an attaching plate 22 the central portion of which is stamped 90 with a recess to receive said portions 18, 19 of the hook as clearly shown in Fig. 4. The plate 22 is secured upon the body by means of rivets or similar fastenings 23 and by bending its upper edges 24 over the top edge of the 95 body 1 as illustrated.

From the foregoing it will be seen that my measure will be exceedingly convenient, and will effect a saving in both time and labor. The suspending hook permits it to be readily 100 hung within a barrel, bin, or the like, and the provision of the hinged or drop bottom and the catch for the same enables it to be quickly emptied without the necessity of removing it from its support or otherwise handling it. 105 When the bottom 3 is swung up to its closed position the catch 7 receives the keeper 6 and retains it in such position; and in order to discharge the contents of the body it is only necessary to press inwardly upon the upper 110 handle end of the catch lever.

It will be understood that my improved

measure may be made in any size, and for measuring any substance.

To permit the bottom 3 of the measure to be conveniently raised to its closed position 5 I may provide upon its upper face a hand piece or loop 24 and I may also provide a cord or other flexible element 25 one end of which is attached to the ring or loop 24 and its other end may hang out of the open top of 10 the measure within convenient reach. It will be seen that when the cord 25 is drawn upwardly the bottom 3 will be raised to its closed position.

Having thus described my invention what 15 I claim is:

1. A measure comprising a body, a hinged bottom for the same, a keeper secured to the bottom and having an upwardly projecting end provided with a shoulder and an inclined portion, a catch lever pivoted intermediate 40 its ends upon the body, and having at its lower end a shoulder and a beveled or inclined portion, a flat spring secured at one end to the body and having its free end bent outwardly and slotted to receive the catch 45 lever, a finger piece upon said bottom, and a cord connected to said finger piece and extending through the measure.
- 20 2. A measure comprising a body, and a

suspending hook for the latter consisting of a rod bent upon itself to provide parallel portions, the latter being bent upon themselves 30 to provide hook arms, an attaching plate recessed to receive the united parallel portions of said rod and having its upper edge bent over the upper edge of the body, and rivets uniting said attaching plate to the body. 35

3. A measure comprising a body, a hinged bottom for the same, a keeper secured to the bottom and having an upwardly projecting end provided with a shoulder and an inclined portion, a catch lever pivoted intermediate 40 its ends upon the body and having at its lower end a shoulder and a beveled or inclined portion, a flat spring secured at one end to the body and having its free end bent outwardly and slotted to receive the catch 45 lever, a finger piece upon said bottom, and a cord connected to said finger piece and extending through the measure.

In testimony whereof I hereunto affix my signature in the presence of two witnesses.

DAVID HOWE.
